BRADFORD BORDEN, OF TORONTO, ONTARIO, CANADA, ASSIGNOR TO THE BORDEN COMPANY, OF WARREN, OHIO, A CORPORATION OF OHIO.

PIPE-THREADING TOOL.

1,048,644.

Specification of Letters Patent.

Patented Dec. 31, 1912.

Application filed February 11, 1911. Serial No. 607,946.

To all whom it may concern:

Be it known that I, BRADFORD BORDEN, of Toronto, in the Province of Ontario, Dominion of Canada, have invented certain new 5 and useful Improvements in Pipe-Thread- 60 ing Tools; and I do hereby declare the following to be a full, clear, and exact description of the invention, such as will enable others skilled in the art to which it 10 appertains to make and use the same.

In some classes of die stocks or pipe 15 threading tools at the completion of the threading operation the chasers, owing to the sudden cessation of resistance, open out- 20 wardly so quickly that the operators are frequently struck by one of the operating handles.

The primary object of this invention is 25 to provide simple and highly efficient means which, while allowing the chasers to open automatically after the cutting operation is completed, will control and render gradual such opening movement.

A further object is to insure the automatic 30 reengagement between the chaser-engaging plates and the controlling post after the chasers have opened outwardly at the end of a cutting operation. And a further object is to adapt the present invention to a 35 tool capable of cutting pipes of different sizes at correct pitch and with threads of proper lengths.

The invention will be hereinafter fully 40 set forth and particularly pointed out in the 35 claims.

In the accompanying drawings, Figure 1 is an end elevation. Fig. 2 is a side view. Fig. 3 is a fragmentary view of the cam plate. Fig. 4 is a view thereof with parts 45 broken away. Fig. 5 shows the cam plate with a single lug. Fig. 6 is a view of the post.

Referring to the drawings, 1 designates 45 the chaser-carrier or housing; 2 the radially movable chasers mounted in guideways of the carrier; 3 lugs projecting from the chasers; 4 the cam or chaser-engaging plate having eccentrically-arranged grooves for taking in the chaser lugs; and 5 a post 50 between which and the chaser-carrier there is a relative longitudinal movement during the rotation of the carrier. In the present instance this relative movement is shown as being obtained by means of a stop 6 with which the end of the pipe is designed

to engage, such stop being carried by a cross bar 7 extended perpendicularly to the axis of the tool and to which at one end is secured the post 5, a corresponding post 8 being secured to the other end of the cross 60 bar. These two posts are shown as extended through sockets of an adjuster 10 which is adjustably secured to the chaser-carrier or housing as contemplated by my pending application for patent Serial No. 584,736, 65 filed September 30th, 1910, the sockets of said adjuster extending through arcual slots 12 of the chaser-carrier, which latter is provided with the ordinary sockets 13 for the reception of the manipulating handles. 70 But so far as concerns the subject matter of the present invention, it is immaterial what means are employed for securing the relative movement between the chaser-carrier and the post which controls the cam 75 plate, which latter, as is well known in the art, while rotating with the chaser-carrier has a movement independently thereof for allowing or causing the chasers to uniformly recede during the threading operation. In 80 the particular instance, the means shown for controlling the independent rotation of the cam plate consists of a diagonally-arranged lug 15 on the inner face of post 5, such lug entering any one of a plurality of 85 cut-outs, or a signal cut-out, in the cam plate. According to the particular means shown the adjustment of the chasers to pipes of different sizes is obtained by releasing the adjuster from the chaser-carrier, and turn- 90 ing it axially, together with the posts, and the cam plate. The means shown for locking the adjuster to the chaser-carrier consists of a handled screw rod 16 projected through threaded openings in parallel ears 95 of a split ring of the adjuster.

My present invention contemplates providing the cam plate with a fixed lug or other element adjacent to each cut-out in the periphery of the cam plate, and the wall of 100 the lug is given a greater slant than the adjacent wall of the cut-out of which it forms a continuation, so that after the chasers cease their cutting operation their disengagement from the pipe will be gradual, thereby 105 avoiding the sudden cessation of resistance. In other words, adjacent to a peripheral cut-out 20 I provide the cam-plate with a lug 21 the face 22 of which is inclined or slightly curved, forming thereby a continuation of 110

one of the walls of the cut-out. The threading operation is completed when the inner end of the diagonally arranged lug of the post passes from between the parallel walls 5 of the cut-out, and in the further revolution of the tool, the cam plate, acting under the pressure of the pipe on the chasers, will be permitted to revolve independently of the chaser-carrier at an accelerated speed, there- 10 by enabling the chasers to gradually open outwardly, the opening movement being controlled by the engagement of the inclined or curved face of the lug of the cam plate with the lug of the post. The rotation of the cam plate relatively to the carrier during the threading operation may be caused wholly by the interlocking engage- 15 ment of the cam plate with the lug of the post, or it may be caused by the outward pressure of the pipe acting on the chasers, the rotation being controlled by the post. But in either event, after the threading operation is completed, the pressure of the pipe on the chasers will give to the cam plate an accelerated movement relatively to 20 the carrier, and this movement is controlled and rendered gradual by the lug on the post.

To adapt a die stock for cutting threads on pipes of different sizes, and in order to 25 obtain the correct length for the different thread pitches, I preferably form the cam plate with a plurality of peripheral cut-outs, a lug being located adjacent to each cut-out. In Figs. 1, 3 and 4, I have shown three cut-outs, with a controlling lug adjacent to two of them, the lugs being of different 30 lengths. In Fig. 5 I have shown a single cut-out with a single adjacent lug.

From what has been said it will be under- 35 stood that as the threading operation progresses the rotation of the cam plate independently of its rotation with the chaser-carrier is controlled by the diagonally-ar- 40 ranged lug of the post between which and the carrier there is a relative longitudinal movement, and that after the threading operation is completed the pressure of the pipe 45 on the chasers will rotate the cam plate, and this rotation while at a greater speed than the rotation of the plate relatively to 50 the carrier during the threading operation is controlled and effects the gradual outward opening of the chasers.

In each of the posts 5 and 8 I have shown 55 screws having milled heads 25 which act as stops upon engaging the rear face of the adjuster, and thereby limit the longitudinal travel between the posts and the chaser-car- 60 rier. These stops prevent the lug of the post moving beyond the plane of the adjacent lug of the cam plate, so that when it is desired to reposition the parts for a second opera- 65 tion, it is only necessary for the operator to bear inwardly on the cross bar, and the engagement of the lug of the post with the

inclined face of the cam lug will so turn such cam plate as to allow the lug of the post to immediately enter the peripheral cut-out of the cam plate. When it is de- 70 sired to remove the chasers, or for any pur- 75 pose to separate the parts, by withdrawing the stop screws 25 the cross bar and the two posts may be withdrawn from the adjuster, or outwardly sufficiently far to enable the lug of the post to clear the lug of the cam 80 plate.

Although I have shown and described the preferred manner of carrying out my in- 85 vention, it will be understood that changes may be made in the construction and ar- 90 rangement of parts without departing from the spirit of the invention.

I claim as my invention:—

1. In a pipe threading tool, the combi- 95 nation with a rotatable and longitudinally 100 movable chaser-carrier, and a series of radi- 105 ally-arranged chasers, of a chaser engaging plate rotatable with, and also relatively to, the chaser carrier, said plate having an in- 110 clined surface of varying inclinations, and a post between which and said carrier there is a relative longitudinal movement, said post having a diagonally-arranged lug for 115 engaging said inclined surface of the chaser 120 engaging plate for controlling the inde- 125 pendent rotation thereof during the thread- 130 ing operation and with which, at the com- 135 pletion of the threading operation, the greater inclination of said surface will en- 140 gage to allow said plate to be turned at an accelerated speed by the pressure of the pipe 145 on the chasers.

2. In a pipe threading tool, the combi- 150 nation with a rotatable and longitudinally 155 movable chaser-carrier, and a series of radi- 160 ally-arranged chasers, of a chaser engaging plate rotatable with, and also relatively to, the chaser-carrier, said plate having in its 165 periphery a diagonally-arranged cut-out and a lug having a surface forming a continua- 170 tion on a greater inclination of one of the walls of said cut-out, and a post between 175 which and said carrier there is a relative longitudinal movement, said post having a 180 diagonally-arranged lug for engaging said 185 cut-out for controlling the independent ro- 190 tation of said plate during the threading 195 operation and with which the inclined face 200 of said lug will engage, after the completion 205 of the threading operation, for controlling 210 the movement of said plate under the pres- 215 sure of the pipe on the chasers.

3. In a pipe threading tool, the combi- 220 nation with a rotatable and longitudinally 225 movable chaser-carrier, and a series of radi- 230 ally-arranged chasers, of a chaser engaging plate rotatable with, and also relatively to, the chaser-carrier, said plate having in its 235 periphery a plurality of cut-outs and a plu- 240 rality of lugs of graduated lengths adjacent 245

to said cut-outs, each lug being inclined in continuation of, but on a greater pitch than, one of the walls of the adjacent cut-out, and a post between which and said chaser-carrier there is a relative longitudinal movement, said post having a diagonally-arranged lug for entering any one of said cut-outs for controlling the independent rotation of the cam plate during the threading 10 operation and with which the lug of the cam plate adjacent the respective cut-out will engage, at the completion of the threading operation, for controlling the movement of said plate under the pressure of the pipe on 15 the chasers.

4. In a pipe threading tool, the combination with a rotatable and longitudinally movable chaser-carrier, and a series of radially arranged chasers, of a chaser-engaging 20 plate rotatable with, and also relatively to, the chaser-carrier, said plate having an in-

clined surface of varying inclinations, a post between which and said carrier there is a relative longitudinal movement, said post having a diagonally arranged lug for engaging said inclined surface of the chaser-engaging plate for controlling the independent rotation thereof during the threading operation and with which, at the completion of the threading operation, the greater inclination of said surface will engage, and an adjustable stop carried by the post for permitting it to be moved to enable its lug to be cleared by the inclined 25 30 35 surface of the plate.

In testimony whereof, I have signed this specification in the presence of two subscribing witnesses.
